(57) **CLAIM**

The ornamental design for a laser sensor for doors, as shown and described.

DESCRIPTION

1. The ornamental design for a laser sensor for doors.
- FIG. 1.1: Front, right-hand perspective view of the laser sensor for doors in accordance with the present design; FIG. 1.2: Front, left-hand perspective view thereof; FIG. 1.3: Front view thereof; FIG. 1.4: Rear view thereof; FIG. 1.5: Top view thereof; FIG. 1.6: Bottom view thereof; FIG. 1.7: Right side view thereof; and FIG. 1.8: Left side view thereof.
The broken lines represent portions of the article that form no part of the claimed design.

1 Claim, 8 Drawing Sheets
